12 Inventor:

John F. Schylander

UNITED STATES PATENT OFFICE.

JOHN F. SCHYLANDER, OF CHICAGO, ILLINOIS.

CABINET.

1,398,744.

Specification of Letters Patent. Patented Nov. 29, 1921.

Application filed January 6, 1921. Serial No. 435,388.

To all whom it may concern:

Be it known that I, JOHN F. SCHYLANDER, a citizen of the United States, residing at Chicago, in the county of Cook and State of Illinois, have invented certain new and useful Improvements in Cabinets, of which the following is a description.

My invention relates to that general class of devices known as cabinets; and especially to those cabinets constructed of sheet metal. Such cabinets are extensively used in offices, factories, and elsewhere, and are especially useful in printing rooms to hold trays containing the fonts of type or galley. The trays or shelves containing the type are usually very shallow, and it is desirable to have as many trays as possible within a cabinet, hence my invention is directed to provide a cabinet frame wherein the tray supports occupy very little space and are adjustable to accommodate various depths of trays.

The invention has among its other objects, the invention of a device of the kind described that is simple, convenient, durable, compact, efficient, dependable and satisfactory for use wherever found applicable. Many other objects, advantages and uses of the device herein shown and described will be obvious to those skilled in the art to which this invention appertains.

To this end my invention consists in the novel construction, arrangement and combination of parts herein shown and described, and more particularly pointed out in the claims.

In the drawings, wherein like reference characters indicate like or corresponding parts throughout the views:

Figure 1 is a vertical elevation of my cabinet frame;

Fig. 2 is a vertical section on the line 2—2 of Fig. 1;

Fig. 3 is a section on the line 3—3 of Fig. 4;

Fig. 4 is a section on the line 4—4 of Fig. 3;

Fig. 5 is a vertical section on the line 5—5 of Fig. 2;

Fig. 6 is a fragmentary detail of one of the upright members;

Fig. 7 is a fragmentary detail of one of the tray-supporting members;

Fig. 8 is a view in elevation illustrating a modified form of stop; and

Fig. 9 is a sectional view of the same taken substantially on line 9—9 of Fig. 8.

A represents the cabinet frame, comprising front and rear vertical upright members 1 and 2, respectively, at the ends of said cabinet, and front and rear uprights 3 and 4 intermediate said end uprights. Top and bottom lateral or frame members 5 and 6 are connected to the front and rear end and intermediate uprights. Each of the frame members is preferably channel-shaped and of sheet metal, each of said channels comprising a web 7 and opposed channel arms 8 at right angles thereto. The channel arms of the uprights are slotted at spaced intervals to provide a series of slots or recesses 9, extending inwardly of the free edges of the channel arms, for a purpose to be hereinafter described.

Tray-supporting members 10 and 11 are provided to receive galleys, trays of type or other material, the members 10 being arranged between the front and rear intermediate uprights 3 and 4, and the members 11 being arranged between the front and rear end uprights 1 and 2.

Each member 10 is preferably channel shaped and of sheet metal, having a web 12, parallel channel arms or side flanges 13 perpendicular to said web, and a pair of arms or flanges 14 extending longitudinally of the members and transversely of the channel arms 13, the arms 14 being adapted to receive and support the trays thereon. The supporting members 10 and 11 are so proportioned that the distance between the parallel opposed arms 13 of the member 10 is substantially equal to that between the outer surface of the parallel channel arms 8 of the member 1, so that when the ends of the webs 12 are placed within the slots 9, the channel arms 13 will overlie the outer sides of channel arms 8 and prevent relative transverse movement therebetween.

Stops 15 are provided at the rear ends of the supporting members 10 and 11, said stops being preferably made integral with said members as by upturning the ends of the parts 14, or in any other suitable manner. These stops serve to abut the trays and limit their movement in one direction on the tray-supporting members. I have hereinafter described a modified form of stop.

The outer or end supporting members are similar to the members 10 except that they are provided with but a single tray-supporting arm or flange 14' projecting laterally on one of the channel arms 13'.

As shown in Fig. 1, each of the central tray-supporting members is adapted to receive or carry the adjacent ends of a pair of trays, the bottom of one tray resting on one of the arms 14, and the bottom of the adjacent tray resting upon the other oppositely extending arm 14. The arms 14' are placed in horizontal alinement with the arms 14, so that they will coöperate therewith to support the trays at their outer sides, while the arms 14 support the trays at the inner sides.

Spacers 16 are arranged at the top and bottom of the cabinet, and at points intermediate the top and bottom if so desired, to reinforce the cabinet, each spacer extending between the front and rear uprights and being detachably secured thereto in any suitable manner, as by screws or nuts 18, or any equivalent therefor. The spacers 16 may be of any desired cross section, as shown in Figs. 3, 4 and 5, the ends of the same are offset laterally so as to form plates 17, said plates having apertures therein to receive the tightening screws and nuts 18.

Top and bottom cover plates 19 and 20, respectively, may be provided, if so desired, these plates being secured to the frame in any suitable manner.

In the modified construction shown in Figs. 8 and 9, the upright 7 and supporting members 10 are similar to those shown in the other figures, except that the upturned stops 15 on the supporting members are omitted. In this construction in place of forming the supporting members with individual stops, I mount a common stop on one or more of the rear uprights. Referring particularly to Fig. 9, 23 represents a stop flanged at 25 and 26 and secured to the central upright by a bolt 24. In this case the members 23 may be similar to one of the supports 10, or the supports themselves may be employed for the purpose and arranged on the uprights. This construction has an advantage in that all of the stops at the ends of the supporting members are in alinement and gives an improved appearance.

In assembling the cabinet, the frame is set up with the front uprights and laterals 1, 3, 5 and 6 removed, then the tray-supporting members 10 and 11 are inserted into the slots 9 of the rear uprights, and the spacers are secured to the rear members. The front uprights and laterals are then positioned so that the slots in the uprights are in alinement with the webs 12 of the members 10 and 11, and the front ends of the spacers are secured to the front frame members. Thus the cabinet when assembled is rigid and yet allows the parts to be easily detached to rearrange and vary the spacing of the supports whenever it is desired to do so.

It will be obvious that the cabinet may be made of any desired size, either to support one, two or more stacks of trays or galleys.

The same may also be arranged in units of one, two or more, and then the several units arranged together to form cabinets of the desired total capacity. In the claims where I specify tray-supporting members, I wish to be understood as meaning that the supporting members are adapted to support trays, galleys, or any other part or parts which may be carried thereby.

Having thus described my invention, it is obvious that various immaterial modifications may be made in the same without departing from the spirit of my invention; hence I do not wish to be understood as limiting myself to the exact form, arrangement, construction and combination of parts herein shown and described, or uses mentioned.

What I claim as new and desire to secure by Letters Patent is:

1. A cabinet comprising upright frame members and tray-supporting members detachably carried thereby, each of said tray-supporting members comprising a web and channel arms, and having a longitudinally extending arm transversely of said channel arms and adapted to receive and support a tray thereon, said last mentioned arm lying in a plane substantially parallel to the plane of said web.

2. A cabinet comprising upright frame members and tray-supporting members detachably carried thereby, each of said tray-supporting members comprising a web and channel arms, and having a pair of longitudinally extending arms transversely of said channel arms, said transverse arms lying substantially in a plane and each being adapted to receive and support a tray thereon.

3. A cabinet comprising upright frame members at the ends and intermediate thereof and tray-supporting members carried by said uprights, each of said tray-supporting members carried by said intermediate upright having horizontally slined transverse arms adapted to support the opposed ends of adjacent trays.

4. A cabinet comprising upright frame members at the ends and intermediate thereof, and tray-supporting members carried by said uprights, each of said tray-supporting members carried by said intermediate uprights having horizontally alined transverse arms adapted to support the opposed ends of adjacent trays, and each of the tray-supporting members carried by said end uprights having a single transverse arm co-operating with the oppositely extending transverse arm of an intermediate tray-supporting member to support a tray therebetween.

5. A cabinet comprising channeled upright frame members and tray-supporting members carried thereby, each of said tray-supporting members comprising a web and

channel arms and having a longitudinally extending arm transversely of said channel arms whereby it may receive and support a tray, said web, channel arms and transverse arm being substantially of equal length, said uprights having slots in their channel arms adapted to receive the ends of the webs of said tray-supporting members, so that the channel arms of said tray-supporting members overlie both sides of the channel arms of said upright members and prevent transverse movement therebetween.

6. A cabinet comprising channeled front and rear upright frame members having a series of slots in the channel arms thereof, a series of channeled tray-supporting members carried by said frame members and having their ends insertible in said slots, the channel arms of said tray-supporting members overlying the channel arms of said uprights so as to interlock therewith and prevent relative transverse movement therebetween, spacers between said front and rear upright frame members, and means for detachably securing spacers to said uprights.

7. A cabinet comprising channeled front

and rear upright frame members, each having a series of slots in the channel arms thereof a series of channeled tray-supporting members carried by said uprights, each comprising a web and channel arms and having a longitudinally extending arm transversely of said channel arms and adapted to receive and support a tray thereon, said transverse arm lying in a plane parallel to the plane of said web, the ends of the webs of said tray-supporting member being insertible into said slots, the channel arms of said tray-supporting members overlying the channel arms of said uprights so as to interlock therewith and prevent transverse movement therebetween, spacers between said front and rear upright members, and means for detachably securing said parts together.

In testimony whereof, I have hereunto signed my name in the presence of two subscribing witnesses.

JOHN F. SCHYLANDER.
